UNITED STATES PATENT OFFICE

JAMES P. DUNNE, OF BUFFALO, NEW YORK

ADJUSTABLE ELECTRIC SIGN FRAME

Application filed April 22, 1930. Serial No. 446,327.

This invention relates to adjustable electric sign frames and an object of the invention is to provide an electric sign frame of the character referred to that is very simple in its method of assembly, strong, compact and durable, thoroughly reliable for its intended purpose, and very simple to manufacture and assemble.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claims hereto appended.

In the drawings wherein like reference characters denote corresponding parts throughout the several views:—

Figure 1 is a side elevation of a sign in accordance with the present invention,

Fig. 2 is a detail vertical section taken substantially on the line 2—2 of Fig. 1, and looking in the direction of the arrows,

Fig. 3 is a side elevation of the panel frame without the panel and showing in dotted lines how the frame may be extended,

Fig. 4 is a perspective view of the top or bottom rail,

Fig. 5 is a perspective view of one of the top or bottom cover strips,

Fig. 6 is a fragmentary side elevation of the arrangement of the rails when the sign is extended,

Fig. 7 is a perspective view of one of the hanger strips,

Fig. 8 is a perspective view of one of the center straps used when the frame is extended,

Fig. 9 is a section on line 9—9 of Figure 6,

Fig. 10 is a section on line 10—10 of Figure 6.

In the drawings wherein for the purpose of illustration is shown the preferred embodiment of my invention 8 indicates a horizontal supporting arm which may be attached at its inner end to a building. Additional reinforcing cables 9 are attached to the arm 8 and

their inner ends may be attached to a building which supports the arm. These cables 9 extend diagonally and downwardly from the building to the top of the arm and provide vertical supports for the arm.

A reflector hood is indicated generally at 10 and consists of a substantially rectangular, open bottom casing 11 having the ends thereof secured to an intermediate portion of the hanger straps 12, 13. The upper ends of the straps are bolted as at 14 to extensions 15 on the clamps 16 to which the cables 9 are anchored. The clamps 16 are disposed about the supporting arm 8.

The interior of the hood 10 is divided by a pair of spaced longitudinally extending partitions 17, 18 that incline downwardly and inwardly from the top wall 19 of the hood and merge at their lower ends in an integral channel 20.

To the outer face of each partition 17, 18, are secured electric light bulbs 21, 22. Thus, it will be seen that light will be reflected from the interior of the hood to the sign panel for illuminating purposes.

There will be described hereinafter, one of the sign units having a frame indicated generally at 23. The frame 23 in the form shown, is substantially rectangular in configuration. The frame 23 includes a top rail 24 and a bottom rail 25, each of which is formed of metal of angular cross section.

The legs of the angles of the top and bottom rails are disposed vertically and horizontally with the angles of each rail confronting each other other to form a pocket to receive the panel 26.

The frame 23 further includes end rails 27, 28 which are also angular in cross section with the angles thereof confronting each other to support the panel 26 therebetween. The ends of the side rails 27, 28 abut the inside edges of the top and bottom rails, as will be clearly understood by referring to Fig. 3 of the drawings.

The rails of the frame 23 are secured together at the corners by means of corner straps 29 which are formed of flat straps of metal bent to a right angle. The ends of the corner straps 29 are bolted as at 30 and 31

to the outer faces of the upstanding legs of the respective rails.

The lower ends of the hanger straps 12, 13 are secured to the vertical legs of the corner straps 29, at the upper corners of the frame for supporting the frame within the channel 20. The solid, opaque sign panel 26 conformably fits within the angles of the rails.

After the panel 26 is inserted in the rails 10 of the frame, four flat strips 32 are secured by means of bolts or rivets 33 to the top and bottom rails and side rails of the frame 23 in a manner to secure the panel 26 in position therein.

15 Referring to Figures 6, 9 and 10 of the drawings, where the construction is shown for extending the frame 23, the lower corner straps 29 are entirely eliminated from the lower ends of the side rails 27, 28. To make 20 the extension, the bottom rail 25 is reversed 180° from that shown in Fig. 3 whereby the angle of this bottom rail is outwardly directed. The ends of this reversed bottom rail 25 are secured to the lower ends of the side 25 rails as at 34. Thereafter, an additional side rail 35 of any desired length is added to each side of the frame so that the upper ends thereof will abut the end portions of the bottom rail 25. Then the lower end portions of the 30 side rails 27, and 28 and the upper end portions of the extension side rails 35 are bolted or riveted as at 36 to a flat strap of metal 37 as clearly shown in Fig. 6 of the drawings.

To the lower ends of the extension side 35 rails 35 is secured a bottom rail (not shown) which is similar in all respects to the bottom rail 25 as shown in Fig. 3 of the drawings, and the corners thereof are secured together by an angular flat corner strap similar in all 40 respects to the strap 29 whereby a continuous polygonal frame is constructed with ease and dispatch.

The extension side rails 35 are angular in cross section with the angles confronting each 45 other similar in all respects to the side rails 27, 28 that have been extended thereby.

When a second panel 26' is used the bottom strip 32 of the upper or first panel need not be used as the bottom edge of the panel 26 50 will be held in place by the flanges of the end members 27 and 28 and the vertical flange of the turned member 25 as shown in Figure 9. These strips 32 must be used to hold the lower panel 26' in place as shown in Figures 9 55 and 10.

In the application of the invention, the hood 10 is first secured to an intermediate portion of the hanger straps 12, 13. The upper end of the frame containing the panel is 60 then inserted in the channel 20 of the hood and the lower ends of the straps 12, 13 are secured to the vertical legs of the upper corner straps 29, thereby supporting the frame within the channel in vertical relation below 65 the hood 10 so that illumination from the

hood is reflected on the sign for displaying advertisements thereon.

The present embodiment of the invention has been disclosed in considerable detail merely for the purpose of exemplification, 70 since in actual practice it attains the features of advantage enumerated as desirable in the statement of the above description.

It is to be understood that by describing in detail herein any particular form, structure, or arrangement, it is not intended to limit the invention beyond the terms of the several claims, or the requirements of the prior art.

Having thus described my invention, what I claim as new is:—

1. In an illuminated sign, in combination, a supporting arm, straps secured at spaced points to the arm and depending therefrom, an open bottom hood extending horizontally between the straps and rigidly secured to intermediate portions thereof, spaced, integrally connected, inclined partitions disposed in the hood and having their connecting portion formed to provide a channel, a substantially rectangular frame having its upper portion engaged in the channel, said frame including side and end rails and angle shaped corner pieces connecting said rails together, said frame extending between the straps and the vertical parts of the upper corner pieces being rigidly secured to the lower portion of said straps, a sign panel mounted in the frame, and lamps mounted in the hood for illuminating the sign panel.

2. In an illuminated sign, in combination, a supporting arm, an open bottomed hood supported thereby, lamps in the hood, a substantially rectangular frame having its upper edge supported in the lower part of the hood at the center thereof, an extension frame composed of a bottom rail and a pair of end rails, straps connecting the ends of the first frame to the upper portions of the end rails of the extension frame, and panels in said frames.

In testimony whereof I affix my signature.
JAMES P. DUNNE.
